CRIMPING MACHINE FOR BOOTS AND SHOES.
No. 329,033. Patented Oct. 27, 1885.

UNITED STATES PATENT OFFICE.

JOHN W. D. FIFIELD AND WILLIAM H. HOLT, OF NORTH BROOKFIELD,
MASSACHUSETTS.

CRIMPING-MACHINE FOR BOOTS AND SHOES.

SPECIFICATION forming part of Letters Patent No. 329,033, dated October 27, 1885.

Application filed April 3, 1885. Serial No. 161,143. (No model.)

To all whom it may concern:

Be it known that we, JOHN W. D. FIFIELD and WILLIAM H. HOLT, of North Brookfield, county of Worcester, and State of Massachusetts, have invented an Improvement in Crimping-Machines for Boots and Shoes, of which the following description, in connection with the accompanying drawings, is a specification, like letters on the drawings representing like parts.

This invention has for its object to improve the machine described in United States Patent No. 304,517, heretofore granted to us, and especially as to the construction and mode of operation of the dogs which engage the corners and other parts of the vamp or upper being crimped. Herein we have provided devices for positively actuating the said dogs at the proper time to thus insure their greater efficiency; and we have also improved the construction of the corner-guide, whereby, instead of operating it by hand, it is actuated automatically.

Our invention consists, essentially, in a form-plate provided with slides or blocks, and an auxiliary jaw provided with cam-slots and arms to support the said jaw, the said auxiliary jaw having co-operating with it a main jaw provided with levers, the said levers actuating the leg and foot dogs to grasp the upper or vamp between the dogs and the said blocks or slides, to operate substantially as will be described; also, in a form-plate cut away and provided with a slide or block having a pivoted catch to hold the slide or block in place, substantially as will be described; also, in a form-plate provided with a block or slide, two arms, two auxiliary jaws pivoted thereon and provided each with a cam-slot, and two main jaws having attached levers and slides moved thereby, having mounted upon them corner-engaging dogs, to operate substantially as will be described; also, in auxiliary jaws provided with notches or projections and with hooks, and the main jaw provided with pivoted catches, combined with form-plates and pins or projections to release the said catches, and by pressure against them insure the descent of the main jaw within the auxiliary jaw; substantially as will be described.

Other features of our invention will be here-

inafter pointed out, and specifically designated in the claims at the end of this specification.

Figure 1 in front elevation represents a machine embodying our present improvements. 55 Fig. 2 is a partial vertical central section of Fig. 1 in the line x x , the arm carrying the crimping-jaw at the front of the machine being in section in the line x' x' , the main and auxiliary jaw at the front of the machine being left in elevation, the parts outside the front jaw being also in elevation. Fig. 3 is a partial elevation of the right-hand end of Fig. 1; Fig. 4, two views of the clamping-plate removed; Fig. 5, a partial cross-section of Fig. 65 1 in the lines x^2 x^2 , x^3 x^3 , one jaw and its carrying-arm being in section and the other in plan view; Fig. 6, an inner side view of the auxiliary jaw; Fig. 7, an inner side view of the rear jaw placed in working position against 70 the auxiliary jaw, the said figure showing the dogs to engage the corners and the foot and leg of the vamp or upper, and the clamping-plate, the main jaw by full and dotted lines being shown in two positions, the full-line position being that when the jaws, having engaged the upper on the form-plate, commence to crimp the boot or shoe. Fig. 8 is an inner side view of the main jaw alone; Fig. 9, a left-hand end view of Fig. 8; Fig. 10, a detail of 75 the leg-engaging dog; Fig. 11, the corner-engaging dog detached; Fig. 12, a detail showing the latch which holds the main jaw in its full-line or normal position, Fig. 7; Fig. 13, a detail on a larger scale of one of the slide-blocks and part of the form-plate.

The main frame-work A, in usual or suitable boxes, (not shown,) sustains the main shaft A' and the shaft A². These shafts are provided with chain-wheels A³ A⁴, over which are passed 90 the chains A⁵ A⁶. The chains A⁵ A⁶ have single and double links, and the holders A⁷ for the form-plates A⁸ are secured to the single links by screws or bolts, as at 2.

The form-plates, preferably of sheet-steel, 95 shaped substantially as shown, are attached at their ends to the form-holders A⁷, and each form-plate is provided with three recesses, in which are placed loosely the slides or blocks a a' a'', composed each of two pieces (see Fig. 100 13) united by screws a³, each of the said slides or blocks having pivoted upon it near one edge

a suitable weighted or other pawl, a^4 , which engages teeth cut into the edge of the form-plate next to each slide or block, the said catches retaining the slides or blocks from 5 moving back toward the instep part 3 of the form-plate until after the latter has descended below the jaws, to be described, the said slides or blocks, aside from the catches, being substantially the same as shown in the patent referred to. The form-plates are provided each with two actuating pins or projections, $a^5 a^6$, one at each end of the form-plate, and projecting from each side of the same, the said pins or projections in the movement of the form- 15 plates striking the catches a^7 , pivoted upon the main jaws B, as shown in Figs. 1, 2, 7, 8, and 9, the hooked ends of the said catches (see Fig. 7, full lines) normally engaging notches a^8 (shown by full lines, Fig. 6) in the auxiliary 20 jaw B' when the main jaw B is in its normal or elevated position, as in full lines, Fig. 7. Each auxiliary jaw B' is bolted by bolts b upon an arm, C, pivoted at C', the said arms at their outer ends, at each side of the frame A, receiving 25 through them bolts C², about which, after passing through the said arms, are placed springs C³, the nuts C⁴ being thereafter applied, the springs permitting the arms and their attached jaws to separate to adapt themselves to the thickness of the leather on the 30 form-plates.

The screws b are extended loosely through holes made in the arms C and through bosses located at the middle of the length of the said 35 arms, (see Fig. 5,) where the outer arm, C, is shown in plan, the inner ends of the said screws b entering the auxiliary jaws B', thus supporting them so that they may rock as on vertical pivots, as in other machines shown in 40 patents granted to J. W. D. Fifield.

Each auxiliary jaw, one of which is shown separately in Fig. 6, has ears b' b' at its lower end, to support the main jaw B in its lowest position, as in dotted lines, Fig. 7, and also 45 cam-slots b² b³ b⁴ and bridges b⁵ b⁶ between openings made into the said auxiliary jaw, cam-pits b⁷ b⁸, and the projection b⁹, cast integral with the said jaw, has forming part of it a tubular guide, b¹⁰.

50 The upper end of the auxiliary jaw B' is grooved to receive the lower serrated member of the corner-guide e, and at its rear side each auxiliary jaw has bolted to it by like bolts, 6, (see Fig. 5,) hooks b¹¹ b¹², the latter extending 55 outward about the rear sides of the catches a⁷, when the hooked ends of the latter are in engagement with the notches a⁸ of the auxiliary jaws, as in Fig. 7, the catches being normally held in engagement therewith by the springs 60 7 7.

As soon as the pins or projections a⁵ a⁶ meet the catches a⁷ in the descent of the form-plates the said pins turn the catches on their pivots and disengage their hooked ends from the 65 notches a⁸, turning the backs of the catches against the hooks b¹¹ b¹², so holding them that the pins or projections a⁵ a⁶ in their further

descent, by acting upon the short arms of the catches, compel the main jaws B to descend in unison with the form-plates; but as soon as 70 the upper ends of the said catches pass below the lower ends of the hooks b¹¹ b¹² the catches turn on their pivot-pins and the pins or projections a⁵ a⁶ pass below the catches, leaving the main jaw at rest. 75

Each main jaw B has pivoted upon it at 8 an elbow-lever, d, at 9 an elbow-lever, d', and at 10 an elbow-lever, d², each lever at its lower end having a roller or other stud, the roller-stud of lever d entering the cam-slot b², that 80 of lever d' the cam-slot b³, and that of lever d² the cam-slot b⁴.

The lever d at one end engages a notch in a slide, e, placed in a groove in the back of the main jaw B, and provided at its upper end 85 with the corrugated or serrated corner-dog e', the said slide e being moved longitudinally by the elbow-lever d as the main jaw is caused to descend, the dog e' during such movement being in contact with the material of the upper 90 or vamp at its corner 12. (See Fig. 1, where the said corner is, however, shown as having passed below the jaws.) The inner side of the corner 12, while the corner-dog e' is in engagement with it, is supported by the block a', and 95 as the form-plate descends the block a' slides in it in the direction of the arrow thereon, Fig. 1, the said block and corner-dog grasping the leather at the corner 12, stretching the said corner. 100

The slide e at its rear side, opposite the corner-dog, is provided with a projection, e², which, when the jaw B is elevated, as in full lines, Fig. 7, enters the notch 14, and as the jaw B is depressed, as stated, the projection e² rides 105 up out of the said depression upon the cam-bridge b⁶, and travels and rests on the said bridge so long as it is desired to stretch the said corners, or while the other dogs to be described act, after which the said projection 110 drops from the bridge into the depression 15.

The lever d² has pivoted upon it at d² a leg-stretching dog, d⁵, which enters a hole, d¹, in the clamping-plate f. (Shown separately in Fig. 4 and in plan in Fig. 7.) The lever d has 115 pivoted upon it in like manner a foot-stretching dog, d⁶, extended through a notch, d', in the said clamping-plate.

The leg and foot of the upper at its edge each side of the corner and at each side of the form-plate is supported opposite the leg and foot stretching dogs d⁴ d⁶, referred to, by the slides or blocks a a², respectively, and as the form-plate is carried down between the jaws B B and the latter are depressed with the 120 form-plate by the pins or projections a⁵ a⁶, the rolls on the levers d d' in the cam-slots b³ b⁴ respectively turn the said cam-levers on their 125 fulcra, causing the leg and foot dogs d⁴ d⁶ to be moved diagonally away from the corner 12, 130 the said dogs co-operating with the blocks or slides a a² from the instep part of the form and in the direction of the movement of the said blocks or slides in the said form-plate.

The dogs d^4 d^6 at their rear sides have each a like projection, 20, at its side next the auxiliary jaw B', the said projection, when the main jaw is elevated, entering recesses 16, and 5 as the jaw B descends the said projections pass out from the said recesses and ride upon the bridges b^7 , where they remain as long as it is desired to stretch the upper or vamp, the projections 20 thereafter dropping into the 10 recesses 17 17.

The clamping-plate f , one in each main jaw, has feet 18, (see Fig. 4,) that rest upon a portion of the main jaw and between it and the auxiliary jaw, as shown in Fig. 2, and at their 15 rear sides, near their upper ends, each clamping-plate f has two lugs, 19, provided each with a roller, 22, each roller entering a pit, b^9 , (see Fig. 6,) in the auxiliary jaw, the said pits at their ends being inclined or cam-shaped.

20 While the main jaw is elevated, as in full lines, Figs. 2 and 7, the rolls 22 act on the inner face of the auxiliary jaw just above the pits b^9 , thus keeping the face of each clamping-plate flush with the inner face of the main 25 jaw; but as the main jaw is forced down, as described, the said rolls enter the pits b^9 , thus permitting the clamping-plates to relieve the leather from pressure, while the dogs referred to and slides or blocks act to stretch the 30 leather; but just before the main jaw reaches its lowest position the rolls 22 ride out of the pit b^9 and the clamping-plates are again returned to their flush position.

The slot b^5 receives through it the pin or 35 stud 23, screwed into the back of the main jaw, and provided at its outer end at the back of the auxiliary jaw with a roll, 24, which latter rests on a lever, 25, pivoted at 26, and connected at its outer end (see Fig. 1) by a 40 strap, 27, with a weight, 28, the strap being extended over a pulley, 29, there being one such lever for each jaw.

As the main jaws are depressed as described, the roll 24, acting on the lever 25, depresses it 45 and lifts the weight, and as the form-plate and the vamp or upper thereon pass from between the lower end of the jaws the said lever 25, acted upon by the weight, rises and lifts the main jaw into its full-line or normal position.

50 The movable parts c' of the corner-guides, serrated at their under sides to co-operate with the serrated portions c , attached to the auxiliary jaw, have shanks c^2 extended down through the guide-tubes c^3 , the lower ends of the said shanks being joined by a collar and pins c^4 with a lever, c^5 , secured to a rock-shaft, c^6 , weighted at c^7 , the said lever having a socket-piece slotted at its side walls for the reception of the pins c^4 .

6c The rock-shaft c^6 has an arm, c^8 , connected with it and extended downward, the said arm having a roller or other stud, 28, which is acted upon by the cam projections 29 30 of a disk, h , secured to the shaft A', the said cams 65 in their rotation acting in succession on the roll 28, and moving the lever c^5 , the rock-shaft, and the lever c^5 , so that the latter raises the

shanks of the movable members c' of the corner-guides, thus lifting them to permit the operator to place the vamp or upper in position at the top of the jaws preparatory to the descent of the form-plate upon the upper, the said cams 29 30, as they pass the roll 28, permitting the movable member c' of the corner-guides to drop and hold the upper while the 75 form-plate acts upon and forces the same through between the jaws, the form-plate gradually drawing the upper from between the corner-guides.

Each shank c^2 , near its lower end, has a roller 80 or other stud, 32, which stands in a somewhat spiral slot, 33, the said stud and slot effecting a partial rotation of the shank and its attached part c' as the shank is raised, thus turning the part c' aside, as in dotted lines, Fig. 5, thus 85 uncovering the grooved parts c , to enable the operator to apply the upper.

The arms C C are permitted by the springs C³ on the bolts C² to separate to accommodate the jaws to the thickness of the upper as the 90 form-plate enters between the opposite jaws, and thereafter it is frequently desirable to lock the bolts C², so that the jaws cannot further separate. To do this we have slotted each bolt C² and the arm C, as shown in Figs. 3 and 5, 95 and have placed in the said slots a locking-bar, h' , provided at each end with a wedge, the said bar having connected with it a hand-lever, h^2 , pivoted at h^3 , the said lever being moved whenever it is desired to lock the said 100 bolts and the arms and jaws in position.

We claim—

1. In a crimping-machine, a form-plate provided with slides or blocks a a' , and the auxiliary jaw provided with cam-slots and arms 105 to support the said jaw, the said auxiliary jaw having co-operating with it the main jaw provided with levers, the said levers actuating the leg and foot dogs to grasp the upper or vamp between the dogs and the said blocks 110 or slides, to operate substantially as described.

2. In a crimping-machine, a form-plate cut away and provided with a slide or block, a' , the said block having a pivoted catch to hold the slide or block in place, substantially as 115 described.

3. A crimping-machine containing the following instrumentalities, viz: a form-plate provided with a block or slide, a' , two arms, C, two auxiliary jaws pivoted thereon and provided each with a cam-slot, b^2 , and two main jaws having attached levers d , and the slides moved thereby, having mounted upon them the corner-engaging dogs, to operate substantially 120 as described.

4. In a crimping-machine, the auxiliary jaws provided with the pits b^9 , combined with the main jaws, and the clamping-plates provided with the projections or rolls to enter the said pits and permit the clamping-plates to 130 retire from their forward position flush with the faces of the main jaws, substantially as described.

5. The auxiliary jaws provided with notches

or projections, as at a^8 , and the hooks $b^{13} b^{13}$, and the main jaw provided with the pivoted catches, combined with the form-plates and pins or projections to release the said catches, 5 and by pressure against them insure the descent of the main jaw within the auxiliary jaw, substantially as described.

6. The auxiliary jaw provided with the toothed plate c and the guide b^{12} , and the movable members c' of the corner-guide, having a shank extended into the said guide, combined with the lever c^5 and rock-shaft, and means, substantially as described, to operate it to lift the movable member of the said corner-guide, 15 substantially as described.

7. The auxiliary jaw provided with the toothed plate c and the guide b^{12} , and the movable members c' of the corner-guide, having a shank extended into the said guide, combined 20 with the weighted lever to pull the movable member of the corner-guide down upon the fixed member c , to operate substantially as described.

8. The jaw B' and its attached fixed member c 25 of the corner-guide, and the guide b^{12} , provided with the irregular slot 33, combined with the movable member c' of the corner-guide and its shank, provided with the pin 32, to enter the slot 33 and turn the member c' aside, substantially as described.

9. The auxiliary jaw, slotted at b^5 , and the

independently movable main jaw provided with the pin or stud, combined with the lever 35 25 and the weight thereon, to raise the main jaw, substantially as described.

10. The auxiliary jaw provided with depressions with a bridge between, and the main jaw and its pivoted levers, having pivoted dogs provided with projections 20, to enter the said recesses and ride upon the said bridges, 40 substantially as described.

11. In a crimping-machine, two endless chains, $A^2 A^2$, parallel each with the other, two shafts, chain-wheels thereon to move the said chains in unison, and form-holders attached 45 to the said chains in pairs, and form-plates attached at each end to the said form-holders, leaving the longitudinal centers of the said plates parallel with the said shafts, combined with two arms, C , and crimping-jaws mounted 50 thereon and extended across the machine parallel with the shafts which drive the said chains, the combination being and operating substantially as described.

In testimony whereof we have signed our 55 names to this specification in the presence of two subscribing witnesses.
